SLIP

Victor L. Sussberg, New York, N. Y.

Application August 2, 1934, Serial No. 738,151

3 Claims. (Cl. 2—73)

This invention relates to undergarments, and particularly to an improved slip, the object being to provide a construction which will give a slenderizing effect while at the same time presenting a desired fullness at the bottom.

Another object of the present invention is to provide an improved slip formed principally of two pieces, one forming a front panel and a bust section extending around the rear so as 10 to provide a fullness at the upper part of the body while presenting slenderizing lines centrally and a fullness at the bottom.

An additional object, more specifically, is to provide a slip formed principally in two pieces 15 with one part cut so that the warp will be at an angle to the circumferential lines and the front part cut at an opposite angle to the rear panel.

In the accompanying drawings—

Figure 1 is a perspective view of a slip disclosing an embodiment of the invention, the same illustrating the front part of the garment mounted on a figure;

Figure 2 is a view similar to Fig. 1 but showing a rear perspective view of the garment;

Figure 3 is a front view of the garment shown in Figure 1 when the same is spread out and lying flat;

Figure 4 is a sectional view through Figure 3 30 on the line 4—4, the garment being opened sufficiently to cause the section to represent an ellipse;

Figure 5 is an elevation of the front panel shown in Figure 1 when the same is spread out;

Figure 6 is a rear view of the panel shown particularly in Figure 2, the same being spread out flat;

Figure 7 is a side view on a reduced scale of the garment shown in Figure 1.

Referring to the accompanying drawings by numeral, 1 indicates the front panel of the garment which is cut on the bias so that the warp threads will be at an angle as shown at 2. The front panel, as illustrated in Figure 5, 45 has a bottom portion 3 of a certain width which tapers on a curved line up to point 4, which is at the waistline. From point 4 the edges of the panel diverge along the respective lines 5 and 6, which lines are preferably substantially straight 50 and are bent again at points 7 and 8 into further diverging lines 9 and 10. When the panel is sewed into the garment as shown in Figure 1, the portions 11 and 12 extend around to the rear. By reason of this construction the waistline 55 is constricted and yet the front part 13 is

given a fullness which takes care of the breast formation without detracting from the slenderizing effect secured at the waistline and below the waistline.

The respective edges of the front panel are 5 connected to what may be termed the rear panel 14, which rear panel has a lower edge portion 15 of a certain width which tapers slightly in substantially straight lines up to the respective points 16 and 17, from which points the garment tapers still further along substantially straight lines 22 and 23. The top of the panel is arc-shaped as indicated at 24, the same being comparatively a flat arc, while panel 1 is provided with an arc-shaped upper end 24, the arc 15 being struck on a comparatively short radius so as to present the right form and front to the garment when completed.

If desired lace 26 could be stitched on to the upper part of the garment and the garment 20 cut away underneath in order to secure a desired ornamentation. By forming the blanks as shown in Figures 5 and 6 and connecting the respective edges together by suitable seams the resulting garment will be as shown in Figures 25 1 to 3, inclusive. It will be observed that the front panel 1 does not occupy the entire front of the garment but only a portion of the front, and that the rear or back panel 14 has side and front portions 27 and 28. By forming the garment as just described and by cutting the respecting blanks on the bias, the garment will naturally conform itself more or less to the shape of the wearer when in use and the perspective lines 29 and 30, shown in Fig. 3, will 30 give a desired shape around the lower part of the busts at each side so that the waistline of the garment will properly fit the waistline of the wearer and the lower part of the garment 35 will fall in natural gentle folds, as illustrated 40 in Figures 1 and 2. It will also be seen that by having the respective seams 31 and 32 spaced inwardly and vertically from the sides there will be no appreciable strain thereon when the wearer sits down, bends over or places the garment under any appreciable strain. Also there 45 will be very little wear on the seams and, consequently, these seams will not be apt to tear or open, as happens in many garments where the seams are located at the sides.

As shown in Figures 1 to 3 preferably there are provided shoulder straps 33 and 34 of any desired kind to provide a desired support so that it will not be necessary to constrict the upper 50 part of the garment tightly against the body. 55

By use of these shoulder straps the upper part of the garment will merely fit against the body in a normal manner and by reason of the bias cut of the material will not only fit in a uniform manner but will conform itself more or less to the shape of the wearer.

I claim:—

1. A slip of the character described including a front panel and a rear panel, said rear panel flaring from approximately the waistline downwardly to the bottom, said rear panel from the waistline downwardly to the bottom of the garment extending from a line at the front, around one side, across the back and around the other side to a line at the front, said rear panel tapering from the waistline upwardly with the upper edge of less length than the width of the person wearing the garment, said front panel having its side edges connected to the side edges of the rear panel, said front panel having a skirt portion flaring from approximately the waistline downwardly to the bottom, and a waist portion flaring from approximately the waistline to the upper end, said waist portion being connected to the tapering part of the rear panel and extending across the front of the person wearing the garment, and across the sides and part of the rear.
2. A slip including a front panel having a skirt portion and a waist portion, a rear panel having a skirt portion and a waist portion, and seams securing the respective side edges of said

panels together, said front panel flaring from the waistline downwardly to the bottom of the slip and the waist portion flaring from the waistline upwardly to the top of the slip, said rear panel flaring from the waistline downwardly to the bottom of the slip and the waist portion tapering from the waistline upwardly to the top, with said seams extending from spaced points on the waistline at the front, diagonally around the sides of the slip, to the top rear thereof at spaced points.

3. A slip including a front panel having a skirt portion and a waist portion, a rear panel having a skirt portion and a waist portion, the skirt portion of said rear panel extending across the rear and across the two sides so that the edges of the rear panel will be positioned at the front, and seams securing the respective side edges of said panels together, the said rear panel tapering from substantially the waistline to approximately half way to the top with a certain taper, and from the top of said certain taper to the top of the panel with a less taper, and said front panel flaring from approximately the waistline to approximately half way to the top with a certain flare, and from the top of said certain flare to the top of the panel with a greater flare, said side portions of said flaring part presenting portions extending around the sides to the rear of the slip.
